CLAIM

The ornamental design for a spill containment system
trough unit with weir flange, as shown.

DESCRIPTION

FIG. 1 is a top perspective view of a spill containment
system trough unit with weir flange, showing my new
design;

FIG. 2 is a top plan view thereof;

FIG. 3 is a bottom plan view thereof;

FIG. 4 is a front elevation view thereof; and

FIG. 5 is a rear elevation view thereof.

FIG. 1

FIG. 2

FIG. 3

FIG. 4

FIG. 5
